UNITED STATES PATENT OFFICE.

EDWARD E. BARTLETT, OF SAPULPA, OKLAHOMA, ASSIGNOR TO BARTLETT-COLLINS COMPANY, OF SAPULPA, OKLAHOMA, A CORPORATION OF OKLAHOMA.

DESIGN FOR A TUMBLER.

Application filed March 27, 1928. Serial No. 26,023. Term of patent 14 years.

To all whom it may concern:

Be it known that I, EDWARD E. BARTLETT, a citizen of the United States, residing at Sapulpa, in the county of Creek and State of Oklahoma, have invented a new, original, and ornamental Design for Tumblers, of which the following is a specification, reference being had to the accompanying drawing, forming part thereof.

The figure is a perspective view of a tumbler showing my new design.

I claim:

The ornamental design for a tumbler, as shown.

In testimony whereof I have hereunto set my hand.

EDWARD E. BARTLETT.
